CLAIM

The ornamental design of a ring having a time piece mounted within its central finger opening, as shown and described.

DESCRIPTION

FIG. 1 is an exploded perspective view showing a time piece which is inserted inside the finger opening of a ring.

FIG. 2 is a side elevational view showing the time piece mounted in the finger opening of the ring.

FIG. 3 is a front elevational view showing the time piece mounted inside the finger opening of the ring.

FIG. 4 is a left elevational view of the ring which has the time piece mounted within its finger opening.

FIG. 5 is a right elevational view of the ring which has the time piece mounted within its finger opening.

FIG. 6 is a rear elevation view of the ring which has the time piece mounted within its finger opening; and,

FIG. 7 is a bottom side elevational of the ring which has the time piece mounted within its finger opening.
